UNITED STATES PATENT OFFICE

92,165

DESIGN FOR A TEXTILE FABRIC

Vincent De Liso, Astoria, N. Y.

Application March 10, 1934, Serial No. 50,994

Term of patent 3½ years

To all whom it may concern:

Be it known that I, VINCENT DE LISO, a citizen of the United States, residing in Astoria, Long Island, in the county of Queens and State of New York, have invented a new, original, and ornamental Design for a Textile Fabric, of which the following is a specification, reference being had to the accompanying drawing, forming part thereof.

The figure is a face view of a piece of lace textile fabric showing my design, including, at the bottom, the selvage edge of the fabric. The

design shown is repeated to the opposite selvage edge of the fabric; i. e., the opposite edge of the fabric is the same as that shown.

The portions of the fabric represented by spaced longitudinally extending continuous lines contrast in color from the rest of the fabric.

I claim:

The ornamental design for a textile fabric as shown and described.

VINCENT DE LISO.
